United States Patent Office

Des. 194,417
Patented Jan. 15, 1963

194,417

FROZEN CONFECTION OR THE LIKE

John F. Piskopus, Nassau County, N.Y.
(702 S. Ocean Ave., Freeport, N.Y.)

Filed Jan. 29, 1962, Ser. No. 68,542

Term of patent 14 years

(Cl. D82—2)

Fig. 1

Fig. 2

FIG. 1 is a front perspective view of a frozen confection showing my new design; and

FIG. 2 is a sectional view thereof taken on the line 2—2 of FIG. 1.

The side not illustrated is the same as the side shown and the back is plain and unornamented.

I claim:

The ornamental design for a frozen confection or the like, as shown and described.
